UNITED STATES PATENT OFFICE

1,962,922

FUSE SWITCH

Theodore Birkenmaier, St. Louis, Mo., assignor to
W. N. Matthews Corporation, St. Louis, Mo., a
corporation of Missouri

Application October 23, 1933, Serial No. 694,769

5 Claims. (Cl. 200—126)

This invention relates to fuse switches, and with regard to certain more specific features, to delayed action, reclosing fuse switches.

The invention is an improvement upon the structure shown in Pittman United States Patent 1,894,056, dated January 10, 1933, and the United States Patent 1,940,575 of Lester Pierce Boll, dated December 19, 1933, for Fuse.

Among the several objects of the invention 10 may be noted the provision of improved, automatically reclosing fuse switches of the class shown in said patent and patent application which shall have time-delayed reclosing features; the provision of apparatus of the class described 15 in which the time delay may be adjusted, and which is automatically placed in operating condition by the normal operation of forcing a fuse cartridge into circuit closing position; the provision of apparatus of this class in which the 20 sequence of fuse closures and periods of time delay are so arranged that a temporarily impaired line may be restored to operation, both when the trouble clears quickly, and when it clears slowly, maximum speed of closure being 25 effected under all conditions usually required to be met; and the provision of apparatus of the class described which shall be thoroughly reliable and economical. Other objects will be in part obvious and in part pointed out hereinafter.

30 The invention accordingly comprises the elements and combinations of elements, features of construction, and arrangements of parts which will be exemplified in the structures hereinafter described, and the scope of the application of 35 which will be indicated in the following claims.

In the accompanying drawings, in which is illustrated one of various possible embodiments of the invention,

Fig. 1 is a side elevation of the switch;

40 Fig. 2 is a front elevation;

Fig. 3 is a fragmentary, enlarged, front elevation of the lower end of the switch, parts being broken away to show a time delay mechanism;

Fig. 4 is a vertical section taken on line 4—4 45 of Fig. 3;

Fig. 5 is a vertical section taken on line 5—5 of Fig. 3;

Fig. 6 is a fragmentary detail of an adjustable cam mechanism, being taken substantially on line 6—6 of Fig. 5;

Fig. 7 is a view similar to Fig. 6 showing an alternate position;

Fig. 8 is a fragmentary side elevation showing the inverted application of a fuse cartridge, the

view being taken substantially on line 8—8 of Fig. 3;

Fig. 9 is a fragmentary detail of a cartridge head; and,

Fig. 10 is a vertical section taken on line 10—10 60 of Fig. 3.

Similar reference characters indicate corresponding parts throughout the several views of the drawings.

A large proportion of fuse "outages" on power 65 circuits are caused by such things as lightning transients which last of the order of one-half to one cycle, or temporary short circuits of somewhat longer duration such as wires temporarily swinging together, tree limbs and animals or the 70 like touching two wires but being soon burned off, and like troubles, which may last from a few cycles to a few seconds or a few moments.

With reclosing switches functioning serially and all closing promptly, the temporary trouble 75 may last long enough to cause a reclosure of several switches and associated blowing of fuses before the trouble clears. In fact, all of a given bank of fuses may be blown in sequence before the trouble clears, thus impairing the usefulness 80 of the switch.

With this invention, if the trouble is quite transient, such as a lightning transient, a quick reclosure is available which avoids undue inconvenience to the current consumer; whereas if the 85 temporary trouble is of a longer duration, there is also available a slower reclosure which encompasses the time required for effecting clearing of the trouble. Furthermore, the slow reclosure is made adjustable so as to suit various expected 90 conditions of operations so that if the slow clearing troubles are on the average of a few seconds in clearing, the time for clearing can be encompassed by the reclosure time, and if the average clearing is of a longer duration, the time of reclosure can be lengthened to encompass the same. Thus, in a single switch clearing may be effected 95 of troubles which require various periods for clearing. At the same time this invention avoids the complications of oil switches and the high 100 cost of these.

Referring now more particularly to the drawings, there is shown at numeral 1 an insulator rack supporting insulators 3, the latter carrying upper and lower brackets 5 and 7 respectively. 105 A line wire connection 9 is provided on the upper bracket 5 and a line wire connection 11 on the lower bracket 7.

The upper bracket 5 carries centrally located spring terminal clips 13 for spring engagement 110

with the flat sides of an upper terminal contact 17 of a central fuse cartridge C. The lower bracket 7 carries a contact portion 15 for engagement with lower trunnions 19 of a lower contact 20 of the cartridge C. This cartridge C is of a general nature of the cartridge described in the United States Patent 1,935,386 of Theodore Birkenmaier, dated November 14, 1933, for Fuse, and has a connection 21 in the upper contact 17 for 10 a fuse link 23 which passes downwardly through an insulating tube 25 of said cartridge C and emerges from the lower end thereof. The insulated tube 25 passes through the lower contact 20.

Exteriorly, the fuse link 23 passes under and 13 over a hinged element 29 of a clamp 27, a leaf spring element 31 forming the other element of the clamp as described in said Birkenmaier patent.

When the link 23 is loaded, the spring 31 is 20 pulled down from the untensioned, dotted-line position 32 shown in Fig. 1, and the clamp 27 is opened by rotating the member 29 counter clockwise and thereafter feeding in the end of the link 23. Then upon release of the link from the 23 hand of the operator, the strained position is assumed as shown in solid lines in Figs. 1 and 3. The spring 31 forces down the element 29, thus closing the clamp 27 to hold the link 23 in strained position in the tube. These points will be clear 20 from Figs. 1 to 4 and 8, and from said Birkenmaier patent.

The upper end of the leaf spring 31 is fastened to a platen 33 which is hinged to the lower contact 20 and which is normally pressed upwardly 33 by a leaf spring 35 reacting against the contact 20.

Said lower contact 20 carries said trunnions 19 which rest in open sockets 37 in the lower contact 15. The sockets 37 being open at the top, 40 provision is thereby made for applying and removing as a whole the central fuse cartridge C.

As may be seen from Fig. 10, the fused cartridge C may be applied to the sockets 37 by inverting the cartridge C. The trunnions 19 rest in 45 the sockets 37 and the cartridge C is then rotated counterclockwise as indicated by the arrow. This swings the upper contact 17 into the spring clips 13.

Referring now to the upper terminal 17 of the 50 cartridge C, shown in Fig. 9, it will be seen to include ears 45 for pivotally supporting a bell crank 47, the latter having a latch arm 49 and a pressure arm 51, the pressure arm being engaged by either corner 53 or 55 of a rocker 57 having an operating ring 59. A coil spring 61 reacting between the upper terminal 17 and the arm 51 of the bell crank 47 tends to normally throw the latch 49 into upward position. However, if a hook of a lineman's extension tool or 55 the like is applied to the ring 59, either upward or downward pressure (in fact any pressure except one directed into the axis of rotation of the member 57) will cause either one of the corners 53 or 55 to press the arm 51 of the bell crank 47, thus causing the latch 49 to be depressed against the reaction of said spring 61.

The cartridge C (as well as identical cartridges L and R, to be referred to) may be provided with the fuse link 23, the same being tensioned by the spring 31 while the cartridge as a whole is separated from the terminals 13 and 15. Thus loaded, the cartridge C may have the trunnions 19 applied to the fixed sockets 37, the whole cartridge then being rotated to the position shown

in Fig. 1, the upper terminal 17 engaging the upper line terminal 13.

The lower bracket 7 also carries sidewardly located sets of ears 63 which support sockets 65 for receiving the trunnions 19 of right- and left-hand cartridges R and L respectively, said cartridges R and L being substantially duplicates of said central cartridge C.

The cartridges R and L are normally pressed clockwise by means of plungers 70 held in bearings 72 and normally pressed forward by coil springs 71. By this means the counterclockwise rotation of either cartridge L or R is effected against the reactions of springs 71 and therefore the cartridges are at all times tensioned to spring

80

85

90

from the vertical position shown in Fig. 1 to the sloping, connected positions parallel to the central cartridge C. They are prevented from swinging clockwise (until released) by means of dogs 73. The dog 73 on the left-hand cartridge L swings 95 under a latch 75 which is fastened to a sleeve 76. The sleeve 76 is mounted on a corresponding shaft 78. The mechanism by means of which blowing of the central cartridge C releases the latch 75 to cause the left-hand cartridge L to 100 spring into circuit-closing position will be described later.

The right hand cartridge R carries a similar dog 73 which when the cartridge is rotated counterclockwise into vertical position passes under 105 a similar latch 75 carried on the rod 78.

From the above it may be seen that both the right and left hand cartridges R and L are applied in the manner shown in Fig. 8 and moved counterclockwise against spring-pressed rams 110 such as shown at 70 so as to place the dogs 73 under the latches 75, one latch being carried on the rod 78 and the other on the sleeve 76. Fig. 4 shows a latched arrangement and Fig. 8 shows an unlatched arrangement.

115

As shown in Fig. 1, no upper terminal spring clips are provided for the cartridges R and L in their vertical positions but such are provided at the ends of a T head 80 in a forward plane with the central spring clip 13. These clips are numbered 81 and 83 for the respective cartridges L and R. Associated with the respective clips are edges 93 which are adapted to be engaged by the ends of the arms 49 upon forward swing of the cartridges R and L (Fig. 1). It will be 125 understood that the central cartridge C cannot pass beyond the sloping position shown in Figs. 1, 2, and 3, the same engaging a stop 82 to prevent this as it is applied. On the other hand, the cartridges L and R have no corresponding 130 stops and pass through their respective contact clips 81 and 83 to the vertical, latched, out-of-circuit positions shown in Figs. 1 to 4.

130

As made clear in said Patent 1,894,056, it is the purpose herein to have all of the cartridges substantially identical and fused as described in connection with cartridge C. The cartridge C is then invertedly applied to the lower contact 15 and rotated counterclockwise to the Fig. 1 position, thereby closing the circuit. Next, a right or left-hand reserve cartridge is likewise applied and rotated through its contacts 81 or 83 as the case may be, to the vertical position. Both right and left hand cartridges are thus treated. Their temporary passage through the circuit closing positions does not change the circuit conditions, because the central fuse has closed the circuit. As in said patent, it is the intention herein to have blowing of the central fuse cartridge C effect release of the left hand

135

140

cartridge so that it may spring into circuit closing position and so that subsequent blowing of the left-hand cartridge shall release the right-hand cartridge so that it may assume a circuit closing position. However, it is desired to avoid the disadvantage of all reserve cartridges reclosing instantaneously. For this reason time delay mechanisms are inserted serially between cartridges C and L and cartridges L and R respectively.

Referring to Fig. 3 such time delay mechanisms are shown at numerals 91 and 93. Inasmuch as both of these mechanisms 91 and 93 are substantially the same, only the mechanism 93 will be described in detail. It comprises a housing 95 attached to the lower bracket 63. This housing 95 contains an escapement mechanism 97. This mechanism comprises an escapement wheel 99 cooperating with an escapement yoke 101, the yoke 101 reciprocating under alternate impulses of opposite teeth on the wheel 99 so as to determine the rate at which the wheel 99 rotates. The wheel 99 is driven by means of a pawl mechanism 103 cooperating with a ratchet 102 fastened to said wheel 99, the ratchet 102 and wheel 99 being loose (as a unit) on the shaft 105. The pawl mechanism 103 is fast on the shaft 105. The shaft 105 carries a pinion 107 which is driven by gear 109 carried on a countershaft 111 with a pinion 113, the latter being meshed with a main segmental gear 114. A drive spring 115 reacts between the case 95 and the segmental gear 114. It will be seen that if the segmental gear 114 is rotated counterclockwise (Fig. 4) clockwise (Fig. 5) so as to wind the spring 115, the gear train will move so as to move the pawl mechanism 103 counterclockwise over the teeth of the ratchet 102. When the winding action ceases, the spring reacts to drive the pawl mechanism 103 clockwise so as to drive the ratchet wheel 102 and the escapement wheel 99. The reciprocation of the yoke 101 determines the rate at which the gear train shall run down.

In order to transmit the action due to running down to release the next cartridge, each segmental gear 114 is provided with a socket 117 which, as the gear 114 rotates clockwise, in due course contacts with the lower end 119 of a push rod 121 which is connected with a crank 123, the latter being attached to the rod 78 in the case of the time delay mechanism 93 and to the sleeve 76 operable from the time delay mechanism 91. Thus it will be seen that the time delay mechanism 91 controls release of the latch 75 for releasing the left-hand cartridge L; whereas the time delay mechanism 93 controls the release of the other latch 75 for releasing the right-hand cartridge R.

Winding of the spring 115 is accomplished by means of the rotation of the respective cartridge into its upper position. To accomplish this each cartridge is provided with a dog 125 which, incidentally, is provided with an extension 127 to give support for the fuse clamp 29. The function of the dog 125 in the present connection is to contact with the lip 129 of a barrel cam 131, the latter being borne on an extension journal 133 within a hollow hub 135 of the gear 114. The cam 131 is laterally slidable on said stud 133 and is spring-pressed toward its respective cartridge by a spring 137 (Figs. 6 and 7). It is not splined directly to the stud 133 but is made adjustable in position with respect to the gear 114 by means of a finger 139 held in a slot 141 in said cam 131. The finger 139 constitutes part of a lever 143 which may be adjusted. The end of the lever is

provided with a locking nut 145 swinging in a calibrated groove 147 of the gear 114. The groove may be calibrated in terms of cycles and/or seconds and/or minutes. Thus movement of a corresponding cartridge into upward position results in contact between the respective dog 125 and lip 129 of the respective barrel cam 131. The barrel cam 131 is fixed with respect to the gear 114 by the adjustable connection consisting of slot 141, finger 139, lever 143 and lock nut 145. The initial relationship between the edge 129 of the barrel cam 131 and the dog 125 may be adjusted by adjusting the lever 143, thus either advancing or delaying the contact between dog 125 and the edge 129. It will be seen that if the contact is delayed, the escapement mechanism will not be wound as much as if the contact is advanced, thus shortening the time it requires for the socket 117 to cause lifting of the rod 121 and release of the corresponding latch 75. Thus, the time delay is accomplished by so relating the barrel cam 131 to the gear 114 which carries the pocket 117 so that the pocket 117 is moved more or less when the respective cartridge is thrown into its upward position. The movement of the pocket 117 is proportional to the winding movement applied to the escapement and thus the escapement runs a longer or shorter time at a constant rate in proportion to the amount that the pocket 117 has moved downwardly. Thus the rate of release is the same but the total time required is different according to the adjustment of the lever 143.

In order that the escapement mechanism may be held in wound position until the respective fuse blows, the barrel cam 131 is made laterally movable on the stud 133 and on the finger 139 and it is provided with a rearward camming surface 149 which, upon moving the respective cartridge up (with winding of the spring 115) contacts with a fixed portion 151 of the respective housing 95. The surface 149 and fixed member 151 by said adjustment become related so that when the respective cartridge is in its upper position the cam 131 is drawn out of contact with the respective dog 125 on the respective cartridge. The gear train would then run down under action of the spring but provision is made against this by means of a latch 153 which catches under the raised lip 129. Up to this time the latch 153 has been riding on the outer surface of the barrel cam 131. The latch 153 is normally pressed to engaging position by the gravitational action of an overhanging arm 155 which reaches forwardly and is adapted to be engaged by a tongue 159 of the respective platen 33 when the platen moves up as the spring 31 is released upon blowing of the respective fuse.

In the case of the left-hand fuse L which goes to a vertical position first and then springs forward to circuit closing position, its respective release arm 155 in mechanism 93 is provided with a springy finger 161 over which rides the platen extension 160 upon upward movement of cartridge L. When the cartridge L returns to circuit closing position the extension 160 positions itself under the finger 161. The reason for this will appear.

The operation is as follows:

Three identical cartridges are loaded, placing the springs 31 as shown in Fig. 8. Their trunnions 19 are applied to the respective sockets after having inverted the cartridges (as in Fig. 8). Although the cartridges are identical they become right hand R or left hand L or center C, depending upon position. The central cartridge 150

C is then forced up into its upper sloping, circuit closing position, shown in Fig. 1, thereby closing the circuit between the line contacts 9 and 11. This central cartridge does not leave 5 this position until the line man again removes it for reloading after it is blown.

Next, the other two cartridges are successively pushed up through their respective upper contacts 81 and 83 to the vertical positions shown in 10 Figs. 1 to 4. They are held vertically by the latches 75. During the movement of the cartridges C and L to their upward positions, the time delay mechanisms have been tensioned and presumably said mechanisms have previously been 15 adjusted for the desired time delay in reclosing the respective cartridges which they control. The barrel cams 131 are drawn out of engagement with the dogs 125 on the cartridges by the engagement of cam surfaces 149 with the fixed 20 stops 151 (see Figs. 6 and 7).

Assuming that the device is set for taking care of short transients and short circuits of longer duration, it will be seen that the time delay mechanism 91 will be set for a reclosure after 25 perhaps only a few cycles of "outage"; whereas the time delay mechanism 93 will be set for reclosure after a more substantial period of time. Thus, assuming that the cartridge C blows, its platen 33 will whip upwardly to pull out and drop 30 the fuse link and to raise the respective arm 155 and thus, through the latch 153, release the barrel cam 131, which being attached to the segmental gear 114 permits the escapement mechanism to run down under the tension of the spring and 35 the socket 117 to move the stem 121 upwardly to open the latch 75 associated with the left-hand cartridge L. This cartridge thus, almost immediately, springs forward under pressure of its ram 70 to circuit closing position in the upper 40 spring contacts 81, thereby reclosing the circuit. It will be understood that the time delay may be made longer if desired by adjusting the mechanism 91 at nut 145.

Then, assuming that instead of being a transient "outage", the time is somewhat longer. This will also cause blowing of the reclosed left-hand cartridge L and it will, in like manner, set off the time delay mechanism 93 which upon running down unlatches the latch 75 associated with the 50 right-hand cartridge R, thus springing the cartridge R into its circuit closing position.

It is preferable that the time delay mechanisms which operate first have the shortest time delay adjustment so that if a transient occurs, 55 a minimum number of reclosures or a single one will take care of it.

It will be further understood that in a set of three cartridges, as herein disclosed, the time delay mechanism 91 could be eliminated and an 60 instantaneous reclosure be made with the left hand cartridge L, as in the case of said Patent 1,894,056. The normal mechanical delay would take care of transients. Then the time delay mechanism 93 between cartridges L and R would 65 be set for a longer reclosure period to take care of temporary short circuits and the like.

It is to be further understood that any number 70 of cartridges may be used in a bank with time delay mechanisms serially arranged between them. Thus each successive time delay mechanism could be set to take care of increasingly longer "outages". The particular number will depend upon 75 circumstances and the expense involved. Simplification may of course be effected by operating several fuses from one time delay mechanism

which would be permitted to run down a fractional distance for each by properly located holding latches associated with the respective cartridges.

In view of the above, it will be seen that the several objects of the invention are achieved and other advantageous results attained. 80

As many changes could be made in carrying out the above constructions without departing from the scope of the invention, it is intended that all matter contained in the above description or shown in the accompanying drawings shall be interpreted as illustrative and not in a limiting sense. 85

I claim:

1. A fuse switch comprising at least two pairs of line terminals, at least two fuse cartridges, means for moving one of said cartridges to circuit closing position, means for moving the other cartridge to an open circuit position, means for tensioning said other cartridge to normally press the same to closed circuit position, a latch for resisting movement to circuit closing position, a time delay mechanism, spring means for operating the time delay mechanism, an escapement for determining the rate of operation of the time delay mechanism, means for tensioning said spring upon applying the circuit closing cartridge, means holding the time delay mechanism in tension while the circuit closing fuse cartridge is unblown, and means responsive to the blowing of said circuit closing cartridge to release the time delay mechanism for operation, and means whereby predetermined movement of the time delay mechanism releases said latch to effect movement of the open circuit cartridge to closed circuit position. 95

2. A fuse switch comprising at least two pairs of line terminals, at least two fuse cartridges, means for moving one of said cartridges to circuit closing position, means for moving the other cartridge to an open circuit position, means for tensioning said other cartridge to normally press the same to closed circuit position, a latch for resisting movement to circuit closing position, a time delay mechanism, spring means for operating the time delay mechanism, an escapement for determining the rate of operation of the time delay mechanism, connective means for tensioning said spring upon applying the circuit closing cartridge, means opening the connection between the circuit closing cartridge and its respective tensioned time delay mechanism and for holding the time delay mechanism in tension while the circuit closing fuse cartridge is unblown, and means responsive to the blowing of said cartridge to release the time delay mechanism for operation, and means whereby predetermined movement of the time delay mechanism releases said latch to effect movement of the open circuit cartridge to closed circuit position. 100

3. A fuse switch comprising at least two pairs of line terminals, at least two fuse cartridges, means for moving one of said cartridges to circuit closing position, means for moving the other cartridge to an open circuit position, means for tensioning said other cartridge to normally press the same to closed circuit position, a latch for resisting movement to circuit closing position, a time delay mechanism, spring means for operating the time delay mechanism, an escapement for determining the rate of operation of the time delay mechanism, means for tensioning said spring upon applying the circuit closing cartridge, means holding the time delay mechanism in ten- 105

sion while the circuit closing fuse cartridge is unblown, means responsive to the blowing of said cartridge to release the time delay mechanism for operation, means whereby predetermined movement of the time delay mechanism releases said latch to effect movement of the open circuit cartridge to closed circuit position, and means for adjusting the amount of tensioning effected by said movement of the closed circuit cartridge whereby the period of time delay in activating the open circuit cartridge is made adjustable.

4. A fuse switch comprising at least three pairs of line contacts, at least three similar fuse cartridges adapted to electrically connect the respective pairs of contacts, means for moving one of said cartridges to circuit-closing position, means for moving the other cartridges to open-circuit positions, means for tensioning said other cartridges to normally press the same to closed-circuit positions, latches for resisting their movements to circuit-closing positions, at least two time-delay mechanisms, spring means for operating the respective time-delay mechanisms, escapements for determining the rates of operation of the time-delay mechanisms, means for tensioning the respective springs upon applying the respective circuit-closing cartridges, means holding the time-delay mechanisms in tension while the circuit-closing fuse cartridge is unblown, means responsive to the blowing of said cartridge to release one time-delay mechanism for operation, means whereby predetermined movement of the last-named time-delay mechanism releases the respective latch to effect movement of the respective open-circuit cartridge to its closed-circuit position, means associated with said last-named cartridge responsive to the blowing of the same adapted to release the other time-delay mechanism for operation, and means whereby predetermined movement of said other time-delay mechanism re-

leases its respective latch to effect movement of the other open-circuit cartridge to closed-circuit position.

5. A fuse switch comprising at least three pairs of line contacts, at least three similar fuse cartridges adapted to electrically connect the respective pairs of contacts, means for moving one of said cartridges to circuit-closing position, means for moving the other cartridges to open-circuit positions, means for tensioning said other cartridges to normally press the same to closed-circuit positions, latches for resisting their movements to circuit-closing positions, at least two time-delay mechanisms, spring means for operating the respective time-delay mechanisms, escapements for determining the rates of operation of the time-delay mechanisms, means for tensioning the respective springs upon applying the respective circuit-closing cartridges, means holding the time-delay mechanisms in tension while the circuit-closing fuse cartridge is unblown, means responsive to the blowing of said cartridge to release one time-delay mechanism for operation, means whereby predetermined movement of the last-named time-delay mechanism releases the respective latch to effect movement of the respective open-circuit cartridge to its closed-circuit position, means associated with said last-named cartridge responsive to the blowing of the same adapted to release the other time-delay mechanism for operation, means whereby predetermined movement of said other time-delay mechanism releases its respective latch to effect movement of the other open-circuit cartridge to closed-circuit position, and means for adjusting the respective tensionings effected by movements of the respective closed-circuit cartridges, whereby the periods of time-delay in actuating the open-circuit cartridges are made individually adjustable.
